UNITED STATES PATENT OFFICE.

JOSEPHINE TRUST AND HENRY TRUST, OF BROOKLYN, NEW YORK.

MECHANICAL MOVEMENT.

1,290,686.

Specification of Letters Patent.

Patented Jan. 7, 1919.

Application filed February 11, 1918. Serial No. 216,538.

To all whom it may concern:

Be it known that we, JOSEPHINE TRUST and HENRY TRUST, citizens of the United States, residing at Brooklyn, N. Y., in the 5 county of Kings and State of New York, have invented certain new and useful Improvements in Mechanical Movements, of which the following is a specification, reference being had therein to the accompanying drawing.

Our invention relates to improvements in mixing and beating machines and has particular reference to a machine adapted for beating, mixing or whipping cream, mayonnaise, or other food products, and is so designed that the action produced upon the material to be whipped simulates the whipping action produced manually as when a fork is used for beating cream in a bowl.

In the accompanying drawings, we have illustrated in Figure 1 in vertical perspective a machine embodying an application of our invention; Fig. 2 is an enlarged detail of a pin holding mechanism for pivotally retaining one of the connecting bars for operating the beater, hereinafter more fully referred to.

3 indicates the standard of the machine provided with a suitable base 4 and a platform 5 upon which may be secured a motor such as 6 to drive the gear 7 upon the shaft 8 which in turn carries the sprocket 9 and disk 10, the latter being pivotally connected at 11 to the connecting rod 12 which 15 in turn is pivotally connected at 13 to the rod 14 mounted to slide vertically in the outer end of the arm 15 as shown. 16 indicates a rod pivotally mounted upon the pin 17 which passes through the lower end of the rod 14 and through the upper end of the bar 16 as shown being engaged at the back by the spring 18 as shown to better advantage in Fig. 2, thus facilitating the removal of the bearing 17 when desired.

45 The lower end of the rod 16 it will be observed is provided with a slot 19 within which the pin 20 travels vertically the same being secured upon the disk 21 upon the shaft 22 which also carries the sprocket 23 50 said sprocket being provided with a chain 24 which also passes over the sprocket 9.

25 indicates a bearing upon the rod 16 providing support for the L-shaped member 26 which is pivotally mounted therein 55 by any suitable means such as the bolt 27, the lower end of said bracket 26 being pro-

vided with a beater such as 28 adapted to be operated in the pail 29 supported in the frame 30 which in turn is pivotally mounted in the bracket 31 at 32 as shown by the 60 pin 33.

34 indicates another bracket secured to the standard 3 by screws or other suitable means such as 35 said bracket being adapted to be raised or lowered by engaging said 65 screws in the several holes such as 36. At the outer end of said bar 34 is a vertical member 37 having secured thereto a bracket 38 provided with pins 39 and 40 projecting laterally and between which the inner end 70 41 of the L-shaped bracket 26 is movable.

From the foregoing it will be seen that as the shaft 8 is rotated by the motor 6 through the medium of its driving pinion 42 and the gear 7, the disk 10 at the outer 75 end thereof will cause the rod 16 to reciprocate vertically, while at the same time through the medium of the sprockets 9-23 and chain 24 the pin 20 of the disk 21 upon the shaft 22 will oscillate said bar 16 80 upon the pin bearing 17 thereby conveying to the L-shaped support 26 through the bearing 25 a vertically and laterally oscillating movement to the beater 28, at the same time the vertical movement of the bracket 85 26 because of its lateral extension 41 between the stops 39-40 will receive an oscillation at the bottom of the L-shaped bracket 26 at right angles to the oscillation produced by the pin 20, thus the beater 28 90 will receive a motion simulating that produced by the hand in whipping cream and similar foodstuffs.

If it is desired to chill the material being whipped, the pail 43 may be supplied 95 with ice or other cooling material said pail being adapted to be supported upon the ring 44 held by the bracket 45 the inner end of which is provided with another ring 46 which surrounds the standard 3, the 100 outer end of said ring 46 having a finger 47 adapted to engage the teeth 48 upon said standard 3 and the inner end of said ring 46 being provided with a toe or abutment 49 adapted to provide support when the 105 finger 47 is engaged by one of the teeth 48 as shown.

Should it be desired to heat water or other material within the outer pail 43 a burner such as 50 may be provided and may be 110 supplied with illuminating gas or other fuel if desired.

Of course it will be understood that various modifications may be made in the construction and arrangement of parts without departing from the spirit of the invention as claimed.

We claim:

1. In a machine of the class described, means for vertically reciprocating a beater, and means for simultaneously oscillating the same in two paths at an angle to each other.
2. In a machine of the class described, means for vertically reciprocating the beater, and transmission below said first mentioned means for oscillating the same in a plane parallel with the plane of its vertical reciprocation.
3. In a machine of the class described, a standard provided with driving means at the top, a tool holder vertically reciprocated by said driving means, secondary

driving means below said first mentioned driving means adapted to oscillate said tool holder.

4. In a machine of the class described, a standard provided with driving means at the top, a tool holder vertically reciprocated by said driving means, secondary driving means below said first mentioned driving means adapted to oscillate said tool holder, and means for producing a second oscillation upon said tool holder at right angles to said first oscillation.

In testimony whereof we hereunto affix our signatures in the presence of two witnesses.

JOSEPHINE TRUST.
HENRY TRUST.
